UNITED STATES PATENT OFFICE.

GEORGE W. LORIMER, OF PIQUA, OHIO, ASSIGNOR TO W. R. KEVE, OF PIQUA, OHIO.

THERMOSTAT.

1,100,383.

Specification of Letters Patent. Patented June 16, 1914.

Application filed August 28, 1912. Serial No. 717,164.

To all whom it may concern:

Be it known that I, GEORGE W. LORIMER, a citizen of the United States, and a resident of Piqua, county of Miami, and State of Ohio, have invented a new and useful Improvement in Thermostats, of which the following is a specification.

My invention relates to thermostats for use in connection with automatic fire alarm 10 or fire extinguishing systems. Its object, more particularly, is to produce such a thermostat as will be extremely sensitive to changes in temperature, constant with respect to its critical point of operation, and 15 readily adjustable with respect to the temperature at which it will operate. Primarily it is designed to cause a change in electrical circuits upon the rise in temperature of the surrounding air to a certain pre- 20 determined point, it operating equally well to close a circuit upon such a rise in temperature or to open one, or to close one and open another, according to the character of 25 the electrical apparatus with which it is associated.

A further object is to provide, in connection with the automatically operated part of my thermostat, such testing means as will permit the manual closing or opening, or 30 closing and opening, of the circuits in the same manner as if automatically done, for purposes of testing not only the thermostat itself, but the associated circuits and pieces of apparatus.

Referring to the accompanying drawing which forms a part of this specification, the single figure there shown is a cross-sectional view of my thermostat.

Referring to this figure, 1 is a base of 40 brass or other suitable metal, which forms the means of attachment for the thermostat, as a whole, to the wall, floor, ceiling or other support to which it is to be secured. Secured rigidly to this base, preferably by 45 screw-threading the parts as shown, is a tube, which I prefer shall be of hard rubber, although it may be of any other suitable substance not affected by moisture and having a relatively high coefficient of expansion 50 with respect to the ordinary metals. This tube 2, besides forming an important mechanical link in the thermostat, also serves the purpose of a containing case for inclosing the more delicate parts. Extending 55 from the base 1 within the tube is a stand-

ard 3, preferably, though not necessarily, integral with the base 1, this also being of metal, such as brass. This standard is provided at its extremity with an angular extension or bracket 4, bored with a cylindrical hole 4¹ for a purpose to be described. Within the standard at a point near its base is an insulating bushing 5 of hard rubber or similar material, the purpose of which is to carry the contact screw 6 in 60 such manner as to rigidly support this screw and to insulate it from the bracket. This screw is threaded into the metal collar in the bushing 5 so as to permit of its backward or forward adjustment, as may be required. The extension 4 of the standard or bracket 3 carries a long flexible contact spring 7, this spring being rigidly secured at its upper end to the extension 4 by one or more screws 8 or other equivalent means. 65 The contact spring 7 carries a contact point 7¹, and the screw 6 a similar contact 6¹, these two contacts being so disposed that when the spring is pressed to the left, as viewed in the drawing, the contacts will engage, thus 70 completing the electrical circuit from the wire 9 leading to the base 1 of the instrument, through the standard 3, extension 4, spring 7, contacts 7¹ and 6¹, contact screw 6 to the other leading in wire 10. At a point 75 slightly below the point of support of the spring 7 there is rigidly secured to this spring, by means of one or more screws 11 or equivalent means, a block or stirrup 12, preferably of brass or other metal. This block is provided on its upper face with a conical recess, as shown, for the reception of one of the points of a compression rod 13, also of 80 brass or similar metal. The upper end of the tube 2 is closed by a metal disk 14, preferably screw-threaded into the end of the tube. Through the center of this closing disk 14 there passes the screw 15, the lower end of which is provided with a conical recess similar to that in the block 12. This screw 15 may be adjusted up or down, as 85 may be required, by means of its screw-threaded connection with the disk 14. The rod 13 is provided with a cone shaped point 90 at each end and is supported between the recesses in the block 12 and the screw 15, as clearly indicated. The hole 4¹ in the extension 4 of the bracket 3 is in alignment with the depressions in the block 12 and screw 15, so that the rod 13 may pass freely there- 95 100 105 110

through and yet be laterally supported thereby to facilitate the assembly of the parts.

For operation the screw 15 is turned down 5 so as to exert sufficient pressure through the rod 13 on the block 12 to cause that block to move down from the normal position in which the spring 7 tends to hold it. This downward movement of the block 12 is permitted by the flexibility of that part of the 10 spring 7 which lies between the block 12 and the supporting projection 4, and results in the spring 7 being flexed to the right of its normal position, as viewed in the drawing. 15 The screw 6 is so adjusted that for normal temperatures its contact point 6¹ will not be engaged by the contact point 7¹ on the spring 7.

The operation of the device depends on 20 the fact that hard rubber has a much greater coefficient of expansion than brass or other common metals. When, therefore, a rise in temperature takes place, the length of the hard rubber tube 2 will increase more rapidly than the length of the combined metal parts extending from the base 1 to the cap 14 within the tube, and, as a result, the screw 15 will have such movement as to relieve the pressure exerted by the rod 13 on the 25 block 12, which will allow this block to move upwardly, as shown in the drawing, and thus permit the spring 7 to assume more nearly its normal position. In doing this, the contact 7¹ will approach the contact 6¹, 30 and at a certain rise in temperature will actually engage it, thus closing the circuit between the leading in wires 9 and 10. Obviously, the amount which spring 7 is deflected from its normal position will depend 35 on the adjustment of the screw 15, and the amount of travel which will be permitted this spring before it actually closes contact will be dependent on the position of the screw 6. By the adjustment of these two 40 screws, therefore, the device may be made to close its circuit for any given temperature.

If desired, an additional standard 16, 45 shown in dotted lines, may be provided if the thermostat is to be required to open a circuit rather than close one, when the predetermined temperature is reached. This standard 16 may carry, by means of an insulating bushing 17, another contact screw 18, also shown in dotted lines. This screw 50 may carry a contact 18¹, coöperating with a contact 7² on the spring 7, the construction of these parts being in all respects the same as those of the contact screw 6 and its co- 55 operating parts, with the exception that the screw 18 and its coöperating contacts are placed on the opposite side of the spring 7 and in such relation that at normal temperatures there will be engagement between the 60 contacts 7² and 18¹, this engagement being

broken when the spring is moved to the left when the critical temperature is reached.

I have shown the standard 16 and its associated contact screw 18 in dotted lines, because for an ordinary circuit closing thermostat these would not be required. If the device is required to hold a circuit closed normally and to open it upon a given rise in temperature, then the contact screw 6 could be omitted. If, however, the thermostat were required to open one circuit and close another, both the screws 6 and 18 and their associated parts would be present. The wire 19 forms a leading in wire for the contact screw 18 in the same manner as the wire 10 does for the screw 6.

I provide for great sensitiveness of the device to temperature changes by so proportioning the parts that a very small downward movement of the block 12 will result 85 in a greatly multiplied movement of the contact end of the spring 7, this end being attained by making the distances from the support 4 to the block 12, and from the spring 7 to the lower point of the rod 13, 90 relatively small with respect to the distance from the block 12 to the contact end of the spring. Almost any degree of sensitiveness can be attained by variations in the relative 95 lengths of these lever arms.

In order that the device may be readily available for testing without in any way affecting the adjustment of its parts, I provide a spring 20, secured at one end to the inner side of the tube 2 by means of the 100 screws or rivets 21. This spring is so bent that its free end will lie adjacent to the lower end of the spring 7. It carries, opposite the lower end of the spring 7, an insulating projection 22, so disposed that when 105 the spring 20 is pressed to the left, as viewed in the drawing, it will serve to press the spring 7 to the left without making electrical contact therewith. I provide a push button 23, extending through the wall of the 110 tube 2, so that a pressure of the finger on this button will, through the spring 20, cause the spring 7 to move so as to break its 115 normally closed contacts 7² and 18¹, if such there be, or to close the normally open contacts 6¹ and 7¹, or to open one pair and close the other, as the case may be. By pressing this button 23, therefore, it is possible not only to test manually the contacts of the thermostat itself, but also to test the operation of whatever circuits or other devices 120 may be associated therewith.

Perhaps the simplest adaptation of my thermostat to useful purposes is to that of an automatic fire alarm system for buildings wherein an ordinary alarm bell and battery may be placed in a circuit in series with the wires 9 and 10 leading from the thermostat. A rise in temperature will, by closing the contacts 6¹ and 7¹, cause the 130

sounding of the alarm and at the same time the system may be tested by merely pressing upon the button 23. Of course, the device is equally adapted for the automatic circuit control of any of the well known fire alarm or fire extinguishing systems.

An inspection of my device will show that the relatively great expansion or contraction of the hard rubber tube, which forms a link 10 between the extremities of the device, causes a relative movement between the extension 4, rigidly secured to one end of the device, and the lower end of the rod 13, connected with the other end of the device. Relative 15 movement of these parts is provided for by permitting the rod 13 to slide within the bracket 4. The spring 7 forms virtually a circuit changing lever, and in order that the very small movement imparted to the power 20 end of this lever by virtue of the sliding action of the rod 13 within the bracket 4 may produce a relatively large movement of the working end of the lever, the ratio between the power end and the working end is made 25 a large one.

Having thus described my invention, what I claim as new and desire to secure by United States Letters Patent is:

1. In a thermostat; a tube of highly expandible material, a base and a cap for said tube, a contact spring-lever within said tube, one end of said spring-lever being rigidly 30

fixed with respect to said base, a thrust rod having pointed ends, a stirrup attached to said spring-lever near its fixed end and engaging one end of said thrust rod, an adjustable bearing in said cap for engaging the other end of said thrust rod, and a stationary contact coöperating with the free end of said spring-lever for controlling an electrical circuit, substantially as described. 35

2. In a thermostat; a tube of highly expandible material, a base and a cap for said tube, a contact spring-lever within said tube, one end of said spring-lever being rigidly 40 fixed with respect to said base, a thrust rod having pointed ends, a stirrup attached to said spring-lever near its fixed end and engaging one end of said thrust rod, an adjustable bearing in said cap for engaging the other end of said thrust rod, a stationary contact coöperating with the free end of said spring-lever for controlling an electrical circuit, and a push button for manually operating said spring-lever to test the electrical 45 circuit, substantially as described. 50

Signed by me at Piqua, county of Miami, and State of Ohio, in the presence of two witnesses.

GEORGE W. LORIMER.
